United States Patent Office.

HENRY S. VROOMAN, OF HOBOKEN, NEW JERSEY.

Letters Patent No. 60,807, dated January 1, 1867.

IMPROVEMENTS IN CHANNELLING MACHINES.

The Schedule referred to in these Letters Patent and making part of the same.

TO ALL WHOM IT MAY CONCERN:

Be it known that I, HENRY S. VROOMAN, of the city of Hoboken, county of Hudson, State of New Jersey, have invented certain new and useful improvements in Channelling Machines; and I do hereby declare that the following, taken in connection with the drawings which accompany and form part of this specification, is a description of my invention sufficient to enable those skilled in the art to practise it.

The invention relates to the details of construction of machines for channelling boot and shoe soles, and to that class of machines generally known as the "McKay Channellers." The invention consists in so applying the arm which carries the knife and groover and the presser-wheel that it may be removed from the machine without withdrawing the pin upon which it springs; in so applying this arm that it may be moved longitudinally to adjust the position of the knife and groover laterally with relation to the edge guide-wheel; in applying the knife and groover to a block so fastened to the arm as to be capable of vertical movement to adjust the depth of cut of the channel; in a provision for adjustment of the groover vertically independently from and relatively to the knife; in the employment of a gauge or setting-plate to determine the position of the knife when replaced after removal from the machine; in slotting out through the edge of the plate the screw holes of the knife-stock to permit removal of the knife without withdrawing the screws; in combining with the rod by which the arm is connected to the base-plate and the spring which holds the arm in position a lifter-lever for raising the arm to enter the sole; and in the manner of applying this rod to the arm. The drawings represent a "channeller" embodying my improvements.

Figure 1, showing a vertical central section; and

Figure 2, an end elevation of the same.

Figures 3, a vertical cross-section on the line $z z$, and

Figure 4, a vertical cross-section on the line $z z$, of fig. 1.

In its general organization with reference to cutting the channel the machine does not differ essentially from the channeller above referred to, the changes and modifications introduced by me being principally for the purpose of rendering the parts more readily adjustable, this general organization being as follows:

A denotes the bed, which, with its standards or housings, B B, makes up the frame-work of the machine, supporting the shaft F, which carries the feed-wheel G; this shaft being driven by the crank I, through gearings D E, and carrying the gear H, meshing into and driving the gear I, fixed on shaft J, which carries the presser-wheel K; this shaft J, turning in bearings in an arm L, which swings vertically on the journal-pin a , fixed in top of the rear standard B. The inner side of wheel G carries the bevel-gear p , meshing into the teeth of the bevel-pinion T, turning on the pin w , the periphery of the upper portion forming the guide against which the edge of the sole is held as it passes between the feed and presser-wheels G K to the action of the knife and groover which cut the channel. This being the general and well-understood construction, my improvements will be now described.

The channelling tool being connected entirely with the arm L, and it being often desirable to inspect these tools without removing them from position with respect to the arm, a means for ready removal of this arm from the machine is desirable, and for this purpose I slot out the bearing b to the outer side of the arm, so that when the front end of the arm is disconnected from the bed A the arm may be slipped from the journal-pin a , or upon the same, whenever desirable so to do, without removing the journal-pin. To still further facilitate the removal of the arm L, it is connected to the rod U (to be presently described) by a sliding-pin, q , extending through the rod and transversely through the arm, the length of its bearings in the arm rendering the employment of a screw and nut to keep it in position unnecessary. The construction of the slot b also gives to the arm a capability of longitudinal movement to carry the cutters to a greater or less distance from the edge of the sole, which longitudinal movement is effected as follows: a sliding-block, M, placed upon shaft J, rests upon a pin, d , projecting from standard B, the block being slotted where it rests upon this pin, as seen at c , this slot permitting vertical movement of the block with the shaft, and longitudinal movement of the shaft and arm together, with respect to the block. An adjusting screw, C, passes through this block, the screw upon its end working in to a female screw formed in the arm L. By turning this screw (which is kept from endwise move-

ment by its head and a collar, d' , fastened upon it) the arm L, and with it the presser-wheel and cutters, will be moved from or towards the edge-wheel T, permitting the distance from the edge of the sole at which the channel shall be cut to be determined by simply turning this adjusting screw C, as will be understood from fig. 1. The rod, U, extends through a stud, V, from the standard B, and has at its lower end a screw, upon which a nut, y, works. Around the rod, between the nut y and stud V, is a stout spiral spring, X, (bearing against washers $r s'$,) the stress of the spring holding the arm L down and through the presser-wheel, keeping the sole pressed firmly enough between the feed-wheel G and wheel K, to insure its progression to the action of the cutters.

The pressure is increased or diminished by turning the nut y. Sometimes, however, it is necessary to reduce or remove this pressure while the machine is in operation or to enter the sole, and for this purpose I apply a lever, W, to the plate A and rod U, as follows: the rod extends loosely through one end of this lever, and between this and its opposite end it turns on a fulcrum-pin supported in a bearing resting upon or projecting from the plate A. The outer end of this lever may carry a hook, to which a pedal strap may be fastened, to be operated by the foot of the operator. By depressing the outer end of the lever the inner end is pressed up against the nut y, and lifts the rod, arm, presser-wheel, and cutters, as will be readily understood.

It is often desirable to vertically move the knife and groover together, with reference to the presser-wheel, to vary the depth of channel without disturbing the relative position of the cutters. For this purpose I attach both cutters to a movable block, N, (or to an auxiliary cutter-block, O, fixed to and projecting from this block N,) instead of fastening them to the head of the arm L; this block N (which is preferably made hollow) being secured to the arm L by a screw bolt g, and held in position by such bolt and a stout spring, f, the extent of projection of the cutters below the horizontal plane of the lower surface of the presser-wheel, or below the lower surface of the gauge v, and the corresponding depth of cut, being regulated and determined by the adjusting screw g, as will be understood from figs. 1 and 3. In applying the knife-stock to the machine, the inclination of the blade is first adjusted by hand and by trial, until it cuts the slit as may be desired. In order that the knife may be reset after removal to the same inclination without the inconvenience of adjusting it in position by trial, I apply a gauge-plate, P, as seen in fig. 5; this plate being fastened to the side of the block by an adjusting screw, i. Now, having set the knife-stock Q in such manner as to bring the blade to its proper inclination, and having fastened the stock in position by the screw h, I set the plate P so that its adjacent sides rest against the sides of the stock Q, and fasten it there by the screw i. This being done, it will be evident that whenever the knife-stock Q has been removed, it may be replaced so as to bring the blade in the exact position it previously occupied, by setting its sides against the edges of the plate P, and there fastening it by its screw, h. Through the top of the casting N passes a bolt, k, which has a screw-thread cut on its lower extremity, and fits into a female screw in the upper end of the vertical rod Z, which carries at its lower end a groover-block, R, (fig. 4,) which is kept from turning horizontally by means of the guide rods m. (See fig. 5.) The groover-block is bored through horizontally for the reception of a circular rod or pin, n, projecting out from the face of the metal plate S, (fig. 3.) The other end of the rod n is provided with a screw-thread, on which turns the screw-nut o. The stock of the groover is slotted out at the upper end, which fits snugly against the under surface of the projecting part of the groover-block R, and when the groover is to be set, its stock is slipped between the block R and the plate S, and the screw-nut o is then turned so as to clamp it firmly in place. A screw, j, projects up from the top of the knife-block O, so as to prevent it from being brought into the path of the parts which control the adjustments of the groover tool. (See figs. 3 and 5.) The holes in the knife-stock Q, through which pass the screws h h, are slotted out (see fig. 5) to the edge of the stock, so as to allow of the removal of the knife without the necessity of withdrawing the screws, as has heretofore been done.

From this description it will be seen that all the adjustments necessary in working these machines are provided for in such manner that the operator may produce whatever changes may be necessary in reference to channelling without the aid of a skilled mechanician. Much difficulty has been heretofore experienced in working this class of machines, but with the changes and modifications introduced by me these difficulties have been mostly overcome.

1. I claim so applying the arm L to the machine that it may be removed from the frame or standards without withdrawing the pin a upon which it swings.

2. Also, the provision for longitudinal movement of the arm to adjust the cutters with reference to the edge guide-wheel, substantially as set forth.

3. Also, in combination with the arm L the block N, (or the auxiliary block O,) carrying the cutters, and made capable of vertical adjustment to simultaneously regulate the depth of cut of the knife and groover, substantially as described.

4. Also, the slotted construction of the knife-stock Q, (in combination with a groover-stock and other parts of a channelling machine,) to permit its removal without withdrawing the screw h, substantially as set forth.

5. Also, in combination with the stock Q the gauge-plate P, for determining the position of the knife when replaced, substantially as described.

HENRY S. VROOMAN.
